ATOMIZING DEVICE FOR INTERNAL COMBUSTION ENGINES

Filed Oct. 21, 1933

UNITED STATES PATENT OFFICE

2,054,070

ATOMIZING DEVICE FOR INTERNAL COMBUSTION ENGINES

Daniel L. Covyeow, Chicago, Ill.

Application October 21, 1933, Serial No. 694,628

6 Claims. (Cl. 261--99)

This invention relates to internal combustion engines, and more particularly to the treatment of the fuel charge, the principal object being to prevent the accumulation of carbon deposits within the combustion chambers and cylinders of the engine, and accomplish an increase in the power and efficiency of the engine.

10 The present application involves an invention and improvement over the subject matter of Letters Patent No. 1,918,898, issued to me on July 18, 1933.

15, 1933. A general object of the construction is to prevent the accumulation of carbon deposits within combustion chambers as aforesaid by providing a suitable liquid and atomizing and spraying the same into the fuel mixture entering the combustion chamber of the engine.

A general object of the invention also is to improve the means for atomizing and spraying the liquid into the fuel mixture.

A specific object of the invention is to provide means for obtaining a better division of moisture particles and a better atomizing and spraying result.

25. Another specific object of the invention is to improve the valve means for the said liquid. To accomplish the above objects I have in the concrete exemplification picked out to illustrate the principle of my invention provided openings permitting a cross current of air, which openings may perform the double function of not only securing a decidedly improved division of the moisture particles, but also a reduction of any vacuum that may exist, as will hereinafter appear.

35. Also I have in the form selected shown a spirally formed valve stem which also yields a decidedly improved result with respect to dividing the moisture. In addition to this, I have provided novel means for centering the valve guide tube.

40 The invention also has for an object the provision of means of the character described which will be simple of construction and assembly and relatively inexpensive.

Others of the objects and advantages attained
45 will hereinafter more fully appear.

The invention will be best understood by reference to the accompanying drawing, forming a part of this specification, and in which:

Fig. 1 is a fragmentary view, in side elevation, illustrating more or less diagrammatically the external parts of an internal combustion engine for automobiles and the like with the apparatus of the present invention applied thereto;

Fig. 2 is an elevational view, partly in section, 55 of the device of my present invention; and

Fig. 3 is an enlarged sectional elevational view of part of the device shown in Fig. 2.

5
part of the device shown in Fig. 2.
The concrete exemplification which I have chosen to illustrate the principle of my invention may be applied generally as shown in the Letters Patent hereinbefore referred to, to which reference is made. The numeral 10, referring to the drawing, designates generally the block or housing of an ordinary internal combustion engine of the type used on automobiles and the like. A fuel intake manifold 11 and an exhaust manifold 12 may be located on the same side of the engine block.

Illustrated conventionally is a carburetor 13 having a pipe 14 leading from a source of hydro-carbon fuel supply (not shown), and being also provided with the usual throttle valve rocker arm 15, an operating rod 16, foreshortened as shown in Fig. 1. The carburetor and the other adjuncts are adjusted in the usual way for the proper operation of the engine, just as though the device of the present invention, which is supplementary in its application and utility, were not applied.

In association with the foregoing parts is a liquid vapor receptacle 17 provided with a screw cap 18, which screw cap 18 is provided with an opening 19 for a function which will hereinafter be more fully explained. The liquid contents of the jar may be either plain water, or a mixture of water and alcohol, or other suitable liquid which may be atomized and sprayed into the fuel mixture entering the combustion chamber of the engine. The screw cap 18 has a central opening in which is fitted a nipple member 20 having a shoulder 21. The nipple member 20 is secured in place relative to the screw cap 18 by virtue of a cap nut 22 which threads on nipple member 20 to cooperate with the shoulder 21 of the nipple member to lock the nipple to the cap. The cap nut 22 has a reduced extension 23, and the cap nut 22 is also provided with an aperture 24, the aperture 24 being on the side of the nut 22 opposite to the opening 19 and being particularly illustrated in Fig. 3, and the two apertures being illustrated in Fig. 2. Also the cap nut 22 is internally 45

threaded for engagement with the upper end of a main wick tube 25 which is provided with threads 26. The tube 25 in the concrete exemplification shown has its upper end terminating with the upper end of the reduced extension 23. At the lower extremity of the tube 25 the same is provided with apertures 27 constituting ports, for a purpose which will hereinafter be evident. A wick positioning tube 28 extends into and is secured by an annular body of solder 29 to the 55

main wick tube 25, as is particularly shown in Fig. 3. The wick positioning tube 28 extends from approximately the plane of the screw cap 18 downwardly a short distance below the cap nut 5 22. At the bottom of the main wick tube 25 may be provided a wire spring 30 which may be coiled or looped once and bent so as to provide arms which extend upwardly within the main tube 25 a short distance from the bottom thereof to clamp 10 against the wall of the tube to hold the spring 30 in place within the main tube 25. The wick 31 has an end 32, and the wick leads therefrom into the interior of the wick positioning tube 28 and downwardly therethrough and through the main 15 wick tube 25 to the bottom thereof, and is passed through the loop of the spring 30, as shown in Fig. 2, and is led back up through the main wick tube 25 and the wick positioning tube 28 over the top thereof and around again on the outside to 20 form another end 33. The ends 32 and 33 are secured in position on the outside of the wick positioning tube 28 by means of coiled wire 34 which winds around the outside of the positioning tube 28 and locks the ends between the wire 25 and the tube, as particularly shown in Fig. 3.

Adapted to be secured to the lower end of the main wick tubing 25 is a gauze or mesh guard 35, which may be of frustro-conical shape, having a gauze bottom 36, making the guard entirely 30 closed when secured to the end of the main wick tube 25 by means of a coil of wire 37, as shown in Fig. 2. The screen or guard 35 functions to prevent the entrance of solid matter into the tube 23, and at the same time permits the passage of 35 liquid into the tube therethrough, the shape of the guard being particularly effective for the purpose. If the bottom of the tube should become clogged the liquid may enter through the cylindrical wall of the guard, and also through 40 the small apertures 21.

Mounted within the nipple member 20 is a supplemental nipple member 38 detachably secured thereto by suitable coupling member 39. Extending downwardly through the supplemental 45 nipple member 38 is a nozzle member 40, turned angularly as at 41, the nozzle member being positioned centrally in the supplemental nipple member 38 by means of a coil of wire 42, shown in Fig. 3. The centering function and operation of the 50 wire 42 will be readily understood by those acquainted with the art. The nozzle 40 extends into the T member 43, which has a leg 44 by which it is secured to the nozzle 40 by means of a body of solder 45, the member 40 extending 55 upwardly through the leg 44 and turned as shown in Figs. 2 and 3 into a central horizontal bore 46 in the T-shaped member 43, which is secured by means of a coupling 41 to the supplemental nipple member 38.

Extending through the nozzle member 40, as 60 particularly shown in Fig. 3, and freely slidable yet restricted, is the stem 48 of a gravity valve 49 which may be supported at rest on valve rest members 50. The stem 48 is provided with a 65 spiral thread 51 to break up the moisture into extremely minute particles as desired. The valve rest members 50 comprise inwardly turned portions of the lower end of the wall of the supplemental nipple member 38, forming in the concrete 70 exemplification shown a pair of horizontal lugs or bearings.

As described in the Letters Patent hereinbefore referred to, the jar 17 may be supported at any 75 convenient location by any suitable means. As

shown in Fig. 1, the jar is supported by a bracket element on the engine block.

The T member 43 may be attached at one end to a pipe 52 by a suitable coupling member, the pipe being tapped into the fuel intake manifold 5 at some convenient point, preferably centrally of the manifold and between the carburetor and the places where the manifold communicates with the combustion chambers of the engine. The pipe 52 may be attached to the stem portion of 10 the manifold, and a suitable pet cock or cut-off valve 53 may be provided in the pipe 52 between the nozzle member 40 and the place of connection with the fuel intake manifold. The pet cock or cutoff valve is normally open and is only closed 15 when it may be desired to dispense with the apparatus of the present invention and in making adjustments of the carburetor or other adjuncts for the particular fuel mixture desired for the 20 operation of the engine, which is done regardless of the application and use of the present invention.

At the end of the T member 43 opposite to the end at which the pipe 52 is attached is a reducing cap 54 which couples the T member 43 to a reducing pipe 55 by means of a coupling 56, said pipe 55 being in turn attached to the delivery end portion of an air heating element 57. For a detailed description of the heating element and associated parts reference is made to the Letters 30 Patent above mentioned.

It will be understood that air is carried from the heating element 57 in a highly heated condition to the nozzle member 40. The liquid in the jar may pass through the screen 35 and be carried 35 upwardly through the main wick tube 25, and the wick positioning tube 28, by the capillary action of the wick 30. It will be understood that the valve member has a plain disc-like head and a central stem portion which fits loosely in the bore 40 of the nozzle member 40, so that while there is free slidability, there is at the same time a restricted space between the stem 48 and the surrounding wall of the nozzle member 40. It should also be understood that the valve member 49 and the lower end portion of the nozzle member 40 are not formed with exact nicety for a perfectly fitted seating engagement, but they are, rather, somewhat loosely formed so that when the valve member 49 is seated against the end portion of the nozzle member 40 there is no complete 50 stoppage of the passageway through the nozzle member, but only restricted checking of the flow is afforded.

As will be understood by those skilled in the 55 art, due to the vacuum in the pipe 52 created by the suction of the engine in operation, the liquid which is brought up into the nipple member 20 by capillary action of the wick 30 and the suction in the main tube 23 and the wick positioning tube 60 28 is taken off in small particles and drawn into the tube 52 and converted into a heated vapor in the tube 52. It will be understood that by providing the spiral threads 51 for the valve stem 48, which is conical in cross-section, the moisture 65 particles are finely divided, and the aerated vapor thus finely divided is eventually carried into the combustion chambers of the engine and mingled with the fuel mixture from the carburetor in the intake manifold. It will also be manifest 70 that the openings 19 and 24 will function to permit a cross-current of air within the tube to function in turn to further finely divide the moisture particles, and at the same time the said openings may also function to reduce any vacuum which 75

may exist within the jar 17. It will also be evident that the coil of wire of spiral spring 42 will function effectually to center the nozzle 40 in relation to the supplemental nipple member 38,

5 which sleeves it concentrically for effective cooperation with the spiral stem 48. It will also be understood that the wick will be positively maintained in place.

Because of the features herein pointed out, and 10 those pointed out in the Letters Patent hereinbefore mentioned, the result will be that the liquid contents of the jar will be more effectively atomized and sprayed into the fuel mixture entering the combustion chamber of the engine, and will 15 effectively prevent or greatly minimize the accumulation of carbon deposits within the combustion chambers and engine cylinders, with great effect also in fuel consumption, power, and efficiency.

20 While I have selected particular devices to illustrate the principle of my invention and perform the functions thereof, such as spiral threads, openings, springs, etcetera, neither of these devices nor their location as shown is essential, and 25 the same may be varied or substituted for without departing from the spirit of my invention.

It is to be understood that the particular construction and arrangement shown in the drawing is for the purpose only of illustrating a practical adaptation of the invention, and the structure may be modified without departing from the spirit and scope of the invention. I, therefore, do not wish to be limited to the precise details of construction set forth, but desire to avail myself 30 of such variations and modifications as come within the scope of the appended claims.

Having thus described my invention, what I claim as new and desire to secure by Letters Patent is:

40 1. An atomizing device of the character described comprising a liquid supply receptacle, a supply pipe for conveying the atomized vapor to the intake manifold of an internal combustion engine, a main wick tube extending within said receptacle, a closure member for said receptacle, a nipple connection between said supply pipe and said wick tube, a nozzle member in said nipple connection, and means for centering said nozzle member relative to said nipple connection interposed between said nozzle member and said nipple connection.

45 2. An atomizing device of the character described comprising a liquid supply receptacle, a supply pipe for conveying the atomized vapor to the intake manifold of an internal combustion engine, a main wick tube extending within said receptacle, a closure member for said receptacle, a nipple connection between said supply pipe and

said wick tube, a nozzle member in said nipple connection, and spring means interposed between said nozzle member and said nipple connection and adapted to serve as a centering device.

3. An atomizing device of the character described comprising a liquid supply receptacle, a supply pipe for conveying the atomized vapor to the intake manifold of an internal combustion engine, a main wick tube extending within said receptacle, a closure member for said receptacle, 10 a nipple connection between said supply pipe and said wick tube, a nozzle member in said nipple connection, means for centering said nozzle member relative to said nipple connection interposed between said nozzle member and said nipple connection, and a valve mounted between said wick tube and said supply pipe. 15

4. An atomizing device of the character described comprising a liquid supply receptacle, a supply pipe for conveying the atomized vapor to 20 the intake manifold of an internal combustion engine, a main wick tube extending within said receptacle, a closure member for said receptacle, a nipple connection between said supply pipe and said wick tube, a nozzle member in said nipple 25 connection, means for centering said nozzle member relative to said nipple connection interposed between said nozzle member and said nipple connection, and a valve mounted between said wick tube and said supply pipe, said valve provided 30 with a spiral stem to impart a swirling motion to the vapor and improve the vaporization.

5. An atomizing device of the character described comprising a liquid supply receptacle, a supply pipe for conveying the atomized vapor to 35 the intake manifold of an internal combustion engine, a main wick tube extending within said receptacle, a closure member for said receptacle, a nipple connection between said supply pipe and said wick tube, a nozzle member in said 40 nipple connection, spring means interposed between said nozzle member and said nipple connection and adapted to serve as a centering device, and a valve mounted between said wick tube and said supply pipe, said valve provided with 45 a spiral stem to impart a swirling motion to the vapor and improve the vaporization.

6. In a charge treating device of the character described, a liquid supply receptacle, a main wick tube extending within said receptacle, a nozzle 50 member communicating with said main wick tube, a wick extending through said main wick tube, and a spiral member extending in said nozzle member, said nozzle member communicating with a supply pipe for conveying atomized vapor to the 55 intake manifold of an internal combustion engine.

DANIEL L. COVYEOW.
